UNITED STATES PATENT OFFICE.

GEORGE E. STEWART, OF ASHLAND, AND ALBERT G. BREWER, OF HOPKINTON, MASSACHUSETTS.

VAMP THROATING AND MARKING MACHINE.

SPECIFICATION forming part of Letters Patent No. 499,050, dated June 6, 1893.

Application filed December 15, 1892. Serial No. 455,299. (No model.)

To all whom it may concern:

Be it known that we, GEORGE E. STEWART, of Ashland, and ALBERT G. BREWER, of Hopkinton, in the county of Middlesex and State 5 of Massachusetts, have invented certain new and useful Improvements in Vamp Throating and Marking Machines, of which the following is a specification.

This invention relates to machines of the 10 class shown in Letters Patent of the United States, No. 475,952, granted to us May 31, 1892, in which a machine is shown, having a vamp-supporting bed or table, and a cross-head movable toward and from said table, 15 and carrying a throating die adapted to cut the throat or opening in a vamp, and suitable marking devices adapted to mark the vamp in such manner as to guide the operator in placing the toe-cap thereon, the bed being 20 provided with suitable gages to properly position the blank with reference to the throating die and the marking devices.

The invention has for its object to provide 25 certain improvements relating to the construction of machine for performing the operations above described, and it consists in the several improvements which we will now proceed to describe and claim.

Of the accompanying drawings, forming 30 part of this specification: Figure 1 represents an end elevation of a vamp throating and marking machines embodying our invention. Fig. 2 represents a top view of the same. Fig. 3 represents a perspective view, showing the 35 part of the mechanism which connects the reciprocating cross-head with the shaft that gives it motion. Fig. 4 represents a perspective view, showing a part of the gage-adjusting mechanism. Fig. 5 represents a sectional view on the line 5—5, Fig. 2. Fig. 6 represents a section on line 6—6, Fig. 1, and a plan view of the parts below said line. Fig. 7 represents a section on line 7—7, Fig. 2. Fig. 8 represents a section on line 8—8, Fig. 6. Fig. 45 9 represents a section on line 9—9, Fig. 6. Fig. 10 represents a perspective view, showing one of the marking devices.

The same letters of reference indicate the same parts in all the figures.

50 In the drawings: *a* represents the bed or table of the supporting-frame, the same being

mounted upon legs or standards *a'*, and provided with a cutting block *a²*, of wood or other material adapted to co-operate with the throating die without injury to the latter, said block 55 being adjustably mounted in an opening in the bed *a*, in position to support the work under the throating die.

b represents a cross-head, which is movable toward and from the bed *a*, and has affixed 60 to it downwardly-projecting rods *b' b'*, which are fitted to slide in ways or sockets in the supporting-frame, their lower ends being connected by a cross-bar *b²*, which cross-bar is adapted to be connected, as hereinafter described, with a connecting-rod *c*, which is continuously reciprocated by a connection with the driving-shaft *d* of the machine, the arrangement being such that, when the cross-bar *b²* is connected with the connecting-rod *c*, 70 the downward movements of said connecting-rod will depress the cross-head *b* against the pressure of springs *b⁴ b⁴* on the rods *b'*, said springs normally raising the cross-head, as shown in Figs. 1 and 7.

e represents the vamp-throating die, which is adjustably secured to the under side of the cross-head *b* in any suitable way, and is arranged to bear, when depressed, upon the upper surface of the block *a²*. We have here 80 shown the die *e* as provided with a transverse bolt *e'*, having near one end a screw-thread *e²*, which is engaged with a tapped orifice in one side of the die, so that rotation of the bolt will cause the die to move laterally, the ends 85 of the bolt resting in fixed sockets formed for their reception in plates *f f'*, which are affixed by screws *f' f'* to the under side of the cross-head *b*. A check-nut *e³*, engaged with the thread *e²*, secures the die to the bolt when 90 turned up against the die. The block *a²* is shorter and narrower than the opening *a⁴* in the bed or table *a*, so that said block can move both longitudinally and laterally to prevent the cutting die from acting at all times 95 in the same place upon the block, and thus to distribute the wear caused by the contact of the cutting die with the block. The block is supported by a slide *a⁵*, which rests upon adjusting screws *a⁶ a⁶*, inserted in a yoke or 100 frame *a⁷*, which projects below the table *a*, said adjusting screws enabling the block *a²*

to be raised or lowered. The slide a^5 rests loosely upon the ends of the adjusting screws, and is engaged with a horizontal adjusting screw a^8 (Figs. 1 and 7), adapted to move the 5 slide a^5 and block a^2 longitudinally, so that the operator may from time to time change the position of the cutting block by a movement of the screw a^8 .

a^9 represents an arm, detachably secured 10 to the table a by means of a screw a^{10} . One end of said arm bears against the rear end of the block a^2 , and is adapted to serve as a stop or support for said block, said arm being adjustable by loosening the screw a^{10} and 15 turning the arm on the screw to any desired position in which the arm may be secured by tightening the screw.

The table a is provided with a slot a^{12} for 20 the reception of the removable printing dies a^{13} , which are detachably secured in said slot in position to mark the under side of the vamp when the cross-head descends, the descent of 25 the cross-head pressing the vamp against the printing dies a^{13} , substantially as shown in our former patent. In this case, we provide one die for printing the number of the shoe, and another for printing the size.

If desired, two or more dies may be arranged 30 to co-operate in printing either the size or the number or both. We have here shown two dies, such as would be employed in printing a mixed number, as $2\frac{1}{2}$, said dies being confined in the slot by means of a screw a^{14} , which 35 clamps the dies against a filling block or piece a^{15} (Fig. 8). The other die, which prints the number, is here shown as provided with the characters $2\frac{1}{2}$, and is secured to a wire arm a^{16} , which is clamped to the table a by means of a screw a^{17} , the arm being bent to form a loop 40 between the sides of which the screw passes, so that the screw is enabled to secure the die attached to the loop in different positions within the slot.

g, g (Fig. 6) represent arms, provided at 45 their inner ends with fulcrum pins $g'g'$, which are fitted to slide in grooves f^2f^2 in the plates ff , said grooves and pivots permitting the arms to be adjusted lengthwise and also to be adjusted laterally, the lengthwise adjustment 50 being permitted by the sliding of the pivots or pins g' in the grooves, while the lateral adjustment is effected by the swinging of the arms g on said pivots, the latter being engaged with the grooves so that they cannot 55 move laterally. The outer ends of the arms g are provided with spurs or markers g^2g^2 , which are intended to mark the toe portion of a vamp at two points at opposite sides of the median line of the vamp, to indicate the 60 proper position for the toe-cap upon the vamp. The outer ends of the arms g are provided with nuts g^3g^3 , pivotally connected to the arms, one nut having a right-hand and the other a left-hand thread.

65 g^4 represents a bolt or rod, having near one end a right-hand thread engaged with one of the nuts g^3 , and near its other end a left-hand

thread engaged with the other nut g^3 , the arrangement being such that the rotation of said bolt will move the marker-carrying ends 70 of the arms g, g simultaneously toward and from each other.

g^8 represents a spring, acting as a brake on the rod g^4 to prevent too free rotation of the latter, said brake being held by a screw g^9 , 75 engaged with a yoke g^{10} , mounted upon the rod g^4 , as shown in Figs. 2 and 6.

It will be seen that the described means for supporting the toe-markers g^2g^2 enables said markers to be readily adjusted to any length 80 and width of vamp.

h (Figs. 1, 7 and 10) represents a marking device, connected with the cross-head b , and arranged to mark the toe portion of the vamp at the center or median line thereof. Said 85 marker is a creasing-blade, formed on a shank h^2 , which is fitted to slide vertically in a slot in a stud h^3 secured to the cross-head b , the stud h^3 being fitted to slide in a horizontal socket in the cross-head, and engaged at its 90 outer end with the free end of a spring h^4 , the opposite end of which is affixed to the cross-head, said spring holding the stud normally in a given position, and permitting it to move endwise in either direction.

h^5 represents a spring, which bears on a loose yoke h^6 , one end of which rests on the stud h^3 and the other end on the shank h^2 . The upper end of the spring is supported by a nut h^7 on a pin h^8 affixed to the stud h^3 . 100 The spring h^5 presses downwardly on the yoke h^6 and shank h^2 , and therefore permits the marker h to bear yieldingly upon the vamp when the cross-head b is depressed.

The driving-shaft d is provided with an eccentric i , which is encircled by a strap i' , connected with the above-mentioned connecting-rod c , which we will hereinafter term the driver, whereby motion is imparted from the driving-shaft to the cross-head b . The rotation of the shaft d and eccentric i imparts a continuous reciprocating motion to the rod or driver c . The upper end of said driver passes through a slot in the cross-bar b^2 connected with the cross-head b , and is provided above said cross-bar with a head or enlargement c' (Fig. 3).

j represents a sliding piece, which we term a clutch, mounted to slide upon the cross-bar b^2 , and provided at one end with a slot j^2 , 120 adapted to receive the driver c below the head c' . The clutch j is normally held by a spring j^3 in the position shown in Fig. 3, the clutch being then out of position to engage the head c' of the driver.

Means are provided whereby the operator may force the clutch j forward in the direction indicated by the arrow x in Fig. 3, so that its slotted end will come under the head c' of the driver, and thus engage said driver 130 when the latter is moved downwardly, such engagement causing the driver to impart a downward movement to the cross-head b against the pressure of the springs b^4 , said

springs raising the cross-head when the driver is raised. The means here shown whereby the operator is enabled to move the clutch, as described, comprise a treadle k , arranged to be depressed by the foot of the operator; a rod k' , connected at its lower end with said treadle; a bell-crank lever k^2 , pivoted at k^3 (Fig. 3) to the supporting-frame, one arm of said lever being connected with the upper end of the rod k' ; another bell-crank lever k^4 , pivoted at k^5 (Fig. 3) to the cross-bar b^2 , and having one of its arms arranged to bear on a pin k^6 on the slide or clutch j ; and a link k^7 , connecting the bell-crank lever k^2 with the bell-crank lever k^4 ; the arrangement being such that the depression of the treadle k causes the rod k' , bell-crank lever k^2 , link k^7 , bell-crank lever k^4 and clutch j to move in the direction indicated by the several arrows in Fig. 3. When the operator releases the treadle k , the spring j^3 withdraws the clutch j from its driver-engaging position, thus stopping the motion of the cross-head, a spring k^8 acting at the same time to raise the treadle.

25 The table a is provided with two pairs of gages, arranged to bear on the edges of the vamp, the gages m m of one pair being arranged to bear upon the edges of the vamp near the toe end, while the gages m' m' of the other pair are arranged to bear on the edges of the vamp near the heel end thereof. Each gage is an arm, pivoted at one end to the table a , and adapted to swing horizontally, and each is provided with an inclined slot m^2 , which receives a pin on an operating yoke. There are two of said yokes, n and n' , both fitted to slide horizontally in slots in the table a , each yoke having two arms. The arms of the yoke n are provided with pins o o , which enter the slots in the gages m m . The arms of the yoke n' have pins o' o' , which enter slots in the gages m' m' . The slots in the several gages are arranged as shown in Figs. 2 and 6, the arrangement being such that a simultaneous movement of the yokes n n' in opposite directions, the yokes moving as indicated by the arrows y y' in Fig. 6, will cause the simultaneous inward movement of all the gages; while a movement of the yokes in the opposite directions will cause a simultaneous outward movement of all the gages. In our former patent, the yokes n n' were arranged to be moved by the hand of the operator to effect the simultaneous adjustment of the gages.

55 To enable the gages to be more conveniently operated, we provide in the present case a treadle p , and the devices intermediate of the treadle and the yokes n n' , whereby said yokes may be operated to throw the gages simultaneously inward by a movement of the treadle caused by the operator's foot. The treadle p is connected by a rod p' with one arm of a bell-crank lever p^2 , said lever being pivoted at p^3 to ears formed on a sleeve q , which is affixed by a set-screw q' to the yoke n' .

r represents a rod, affixed to the yoke n by a set-screw r' , and passing through a sleeve q , said rod r being movable lengthwise in a guide or socket in the table a . The rod r $7c$ contains a slot r^2 , which receives the shorter arm of the bell-crank lever p^2 . When the longer arm of the lever p^2 is depressed by the depression of the treadle p , the power thus exerted acts to force the rod r and yoke n toward the left, as viewed in Fig. 5, and the sleeve q and yoke n' toward the right, as indicated by the arrows in Fig. 4, thus causing the simultaneous inward movement of the gages m . When the treadle p is released, a spring p^5 (Fig. 4), connected at its end p^6 with the supporting-frame by means not shown and at its other end with the rod p' and lever p^2 , raises said rod and lever and moves the yokes n n' in directions opposite those indicated in Fig. 4, thus simultaneously throwing the gages m outwardly. It will be seen that, by the described means for operating the gages, the operator's hands are left free for other purposes. The extent to which the yokes n n' may be moved in the direction indicated by the arrows is governed by a screw p^8 , which is inserted in the table a , and passes through a slot p^9 (Fig. 5) in an ear p^{10} formed on the sleeve q .

95 The table a is provided with slots s s , in which are located slides s' s' , which are provided with upwardly-turned ears or stops s^2 s^3 , projecting above the table a and serving as gages for the rear end of the vamp. The slides s' s' are connected at their rear ends by a cross-bar s^8 , which enables them to be moved in unison to adjust the gages s^2 .

s^4 represents a finger, which is pressed downwardly by a screw s^5 upon one of the slides s' as a brake or device to prevent loose movement of the slides s' in their slots s .

We claim—

1. In a vamp-throating machine, the combination of a supporting bed or table having an opening or slot, a cutting block movable horizontally in said opening, a slide supporting said block, and an adjusting screw engaged with said slide and adapted to move the slide and block horizontally, as set forth.

110 2. In a vamp throating and marking machine, the combination of a vamp support, a cross-head movable toward and from said support, mechanism for reciprocating said cross-head, plates affixed to said cross-head and provided with grooved seats, marker-carrying arms bearing on said seats and having pivots fitted to turn and slide in the grooves in said seats whereby said arms may be adjusted both lengthwise and laterally, and a right and left screw rod connecting the outer ends of said arms, as set forth.

115 3. In a vamp-marking machine, the combination of a vamp support, a cross-head movable toward and from said support, a stud inserted horizontally in a socket in said cross-head and movable lengthwise therein, and a

center marker vertically movable in said stud and provided with a depressing spring, as set forth.

4. The combination of the supporting-frame having a vamp support, the cross-head movable toward and from said support and provided with a yoke projecting below the vamp support, a rod or driver continuously reciprocated by the driving-shaft of the machine, a sliding clutch on said yoke adapted to be moved into engagement with said driver and normally disconnected therefrom, and means controlled by the operator whereby said clutch may be engaged with the driver, as set forth.

5. The combination of the supporting-frame having a vamp support, the cross-head movable toward and from said support and provided with a yoke projecting below the vamp support, a rod or driver continuously reciprocated by the driving-shaft of the machine, a sliding clutch on said yoke adapted to be moved into engagement with said driver, a spring which normally removes the clutch from its driver-engaging position, and a treadle and intermediate devices connecting the treadle with the clutch whereby the clutch may be engaged with the driver, as set forth.

6. In a vamp throating and marking machine, the combination of the frame having a vamp support or table, the side gages pivoted to the table and arranged in pairs, the horizontally-movable yokes one engaged with one pair of the gages and the other with the other pair, the engagement of the yokes with the

gages being such that the simultaneous movement of the two yokes in opposite directions will move the gages at one side of the table in the opposite direction from the gages at the opposite side, an operating device such as a treadle arranged to be moved by the operator, and connections between said treadle and yokes whereby the yokes may be moved simultaneously in opposite directions by movement of the treadle, as set forth. 40 45

7. In a vamp throating and marking machine, the bed or table *a*, having slots *s s*, combined with the connected slides *s' s'* movable in unison in said slots and provided with gages *s² s²* projecting above the table, and a brake device engaging one of the slides, as set forth. 50

8. In a vamp throating and marking machine, the combination with the cross-head having the throating die and marking devices, of the table having an opening *a¹²*, the movable printing dies in said opening, the screw *a¹⁴* arranged to hold one set of dies, and the wire arm *a¹⁶* engaged with another die and adjustably secured to the table, as set forth. 55 60

In testimony whereof we have signed our names to this specification, in the presence of two subscribing witnesses, this 1st day of December, A. D. 1892.
